UNITED STATES PATENT OFFICE.

URIAH A. CLEVELAND, OF HUTCHINSON, KANSAS.

CUTTER-BAR FOR HARVESTERS.

SPECIFICATION forming part of Letters Patent No. 644,060, dated February 27, 1900.

Application filed June 24, 1899. Serial No. 721,767. (No model.)

To all whom it may concern:

Be it known that I, URIA A. CLEVELAND, a citizen of the United States, residing at Hutchinson, in the county of Reno and State 5 of Kansas, have invented certain new and useful Improvements in Cutter-Bars for Harvesters, of which the following is a specification.

The invention relates to improvements in 10 ball-bearings for cutter-bars, the object being to produce a structure of this kind that is simple, cheap, and effective; and with this object in view my invention consists of the parts and combination of parts, as will be 15 hereinafter more particularly pointed out.

In the drawings, Figure 1 is a top plan view of a cutter-bar and guard with my improvement embodied, the cutter-bar being broken away. Fig. 2 is a central longitudinal section on the line $x-x$, Fig. 1. Fig. 3 is a perspective view of the clamping-plate detached and inverted. Fig. 4 is a top plan view of the guard and its bar, the bar being broken away.

25 1 is the guard-bar, of suitable construction; 2, the guard-fingers extending therefrom.

3 3 is the ball-seat formed in the guard-finger, provided with slots or openings 4 in the bottom of the same.

30 5 are cut-away portions of the guard-finger between the ball-seat and the outer end of said finger, the object of which is to reduce friction to a minimum. This guard-finger, of course, it is obvious, may be of any approved 35 construction.

6 is the ball working in the ball-seat formed in the guard-finger.

7 is the clamping-plate, of the general outline shown, provided with the bolt-opening 8, 40 through which the bolt 9 is adapted to pass, thereby securing said plate to the guard-bar. 10 is the nut on said bolt.

11 are flanges or projections extending downwardly from plate 7. These flanges form, when 45 the plate is in position on the guard-bar, the ends of the ball-seat 3 in the guard-finger, inasmuch as they extend below the plane of the top of the ball used in said seat 3, thereby confining the ball 6 within said seat.

50 12 are parallel flanges depending from the forward end of the clamping-plate, forming

the ball-seat 13, circular in cross-section, having at each end a V-shaped cut 14.

15 is a guard or flange extending from the top of the outer flange 12, below the lower 55 edge of the same, and given a slight outward bend, as more clearly shown in Figs. 2 and 3.

16 is a ball secured within the ball-seat 13 and adapted to freely work therein.

17 is the cutter-bar, to which is secured in 60 a suitable manner the usual knife 18. The rear edge of the cutter-bar is concaved, as at 19, said concave portion bearing in action against the ball 6.

From Fig. 2 it will be readily seen that the 65 balls 16 and 6 are free in their seats and that they bear, respectively, on the rear edge and on the top of the cutter-bar, thereby holding the bar from two directions firmly on its seat and reducing the friction to a minimum, at 70 the same time holding the bar in its proper working position. Any accumulation of dirt or other foreign matter in the ball-seat 3 passes out of said seat through the slot or openings 4 in the bottom of the same. In 75 order to protect the ball-bearing 13 against knocks, as well as dirt and other foreign matter, I provide the outwardly-extending curved flange 15, which not only prevents the entrance and accumulation of dirt in the seat 80 13, but also prevents the seat from being bent or otherwise injured from knocks resulting from careless use. It will also be readily seen that the usual up-and-down or vertical motion of the cutter or sickle bar is obviated in my 85 construction by reason of the concave face 19 of the bar engaging the center of the ball 6 and, further, by reason of the bearing of the ball 16 on the top of the cutter or sickle bar.

What I claim, and desire to secure by Let- 90 ters Patent, is—

1. In a machine of the character described, the combination with the guard-finger having a ball-bearing near its rear end, of a clamping-plate having downwardly-projecting 95 flanges extending downward at the ends of the ball-bearing and forming stops at each end of the same, a ball-seat projecting downwardly from the forward end of the clamping-plate and a flange extending downwardly and outwardly from the outside of said ball-seat, substantially as described.

2. In a machine of the character described, the combination with the guard-finger, a cutter or sickle bar mounted thereon, of a clamping-plate extending over said cutter-bar, depending curved flanges extending from the forward end of said clamping-plate and circular in cross-section to form a ball-bearing, a ball mounted in said bearing and a flange extending downwardly from the top of said bearing, substantially as described.
3. In a machine of the character described, the combination with the guard-finger, of a ball-seat formed near the rear end of the same, slots or openings in the bottom of said seat, a cut-away portion in said finger in front of the ball-seat and a cutter or sickle bar mounted on said finger, a concaved face or bearing

formed on the rear edge of said bar, a ball mounted in the bearing of the guard-finger, of a clamping-plate, and depending flanges extending downwardly from said plate over the ends of the ball-seat in the guard-finger, parallel depending flanges curved in cross-section extending from the forward edge of the clamping-plate, a ball mounted between said flanges and a flange extending downwardly and outwardly from the top of the seat formed by the parallel flanges and means for connecting said clamping-plate to the guard-finger.

URIAH A. CLEVELAND.
